(57) **CLAIM**

I claim the ornamental design for a crystal pyramid sound generator, as shown and described.

DESCRIPTION

FIG. 1 is a perspective view of a crystal pyramid sound generator showing a first embodiment of my new design;

FIG. 2 is a bottom view thereof;

FIG. 3 is a top view thereof;

FIG. 4 is a front view thereof;

FIG. 5 is a rear view thereof;

FIG. 6 is a left side view thereof, the right side view being a mirror image of the left side view;

FIG. 7 is a perspective view of a crystal pyramid sound generator showing a second embodiment of my new design;

FIG. 8 is a bottom view thereof;

FIG. 9 is a top view thereof;

FIG. 10 is a front view thereof;

FIG. 11 is a rear view thereof;

FIG. 12 is a left side view thereof, the right side view being a mirror image of the left side view;

FIG. 13 is a perspective view of a crystal pyramid sound generator showing a third embodiment of my new design;

FIG. 14 is a bottom view thereof;

FIG. 15 is a top view thereof;

FIG. 16 is a front view thereof;

FIG. 17 is a rear view thereof; and,

FIG. 18 is a left side view thereof, the right side view being a mirror image of the left side view.

The broken line showing of a center object in FIGS. 7-12 is included for the purpose of illustrating environment and forms no part of the claimed second embodiment of the design.

The broken line showing of a center object attachment rod in FIGS. 13, 17, and-18 is included for the purpose of illustrating environment and forms no part of the claimed third embodiment of the design.

The broken line showing of an attachment structure in FIGS. 1, 3-7, 9-13, and 15-18 is included for the purpose of illustrating environment and forms no part of the claimed design.
